EX
OR D 13.032

DESIGN FOR FRINGE.

Design No. 13,032, dated July 11, 1882.

UNITED STATES PATENT OFFICE.

HENRY A. KEHRENBURG, OF PHILADELPHIA, PENNSYLVANIA, ASSIGNOR
TO THE FAIR HILL MANUFACTURING COMPANY, OF PENNSYLVANIA.

DESIGN FOR FRINGE.

SPECIFICATION forming part of Design No. 13,032, dated July 11, 1882.

Application filed May 24, 1882. Term of patent 3½ years.

To all whom it may concern:

Be it known that I, HENRY A. KEHRENBURG, a citizen of the United States, residing in the city and county of Philadelphia, State of Pennsylvania, have invented and produced a new and original Design for Fringe, of which the following is a specification, reference being had to the accompanying photographic illustration, forming part thereof.

10 A represents the heading of the fringe, and B the body thereof. The head is formed of parallel stripes *a*, to the lower one of which are attached the strands *b*, constituting the body. The stripes *a* are connected to each other by 15 short vertical strands *c*, interwoven with the stripes, and the upper stripe is wider than the

other stripes, the fringe thus presenting a neat and attractive appearance.

I claim—

1. The design for fringe, consisting of the 20 heading formed of parallel stripes *a*, united by strands *c*, and the body formed of strands *b*, substantially as set forth.

2. The design for fringe, having a heading formed of parallel stripes *a*, united by strands, 25 the upper stripe being wider than the other stripes, substantially as set forth.

H. A. KEHRENBURG.
